[57] CLAIM

The ornamental design for a container for medicinals,
substantially as shown and described.

DESCRIPTION

FIG. 1 is a perspective view of a container for medicinals showing our new design;
FIG. 2 is an elevational view;
FIG. 3 is an elevational view showing the side opposite
that seen in FIG. 2;
FIG. 4 is a top plan view;
FIG. 5 is a bottom plan view;
FIG. 6 is an elevational view looking from the left of
FIG. 3; and
FIG. 7 is a perspective view showing a modified form
of our new design.

FIG. 1

FIG. 4

FIG. 5

FIG. 6

FIG. 2

FIG. 3

FIG. 7
